UNITED STATES PATENT OFFICE.

FRED SEXAUER, OF TORRINGTON, CONNECTICUT.

SAFETY RAZOR.

Application filed November 28, 1923. Serial No. 677,407.

To all whom it may concern:

Be it known that I, FRED SEXAUER, a citizen of the United States, and a resident of the city of Torrington, county of Litchfield, 5 and State of Connecticut, have invented certain new and useful Improvements in Safety Razors, of which the following is a specification.

This invention relates to razors and more 10 particularly to a safety razor so constructed that the correct diagonal stroke will be more easily obtained by the user.

One object of this invention is to provide a safety razor having a thin flat handle arranged 15 in such a position that the blade will be drawn across the face of the user at the most efficient shaving angle.

A further object is to provide a safety razor of this nature which will be simple, 20 cheap to manufacture, easy to manipulate, and very efficient and durable in use.

With these and other objects in view, there 25 have been illustrated on the accompanying drawings two forms in which the invention may be conveniently embodied in practice.

Fig. 1 represents a side view of a safety razor embodying a preferred form of the invention, looking in a direction at right angles to the plane of the handle, said razor 30 being of the well-known "Gillette" type.

Fig. 2 is a top plan view of the safety razor shown in Fig. 1.

Fig. 3 is a side view of the razor handle, showing in section the screw socket by which 35 it is secured in position.

Fig. 4 is a sectional view of the hollow locking tube.

Fig. 5 is a top view of the razor guard.

Fig. 6 is a similar view of the razor blade.

40 Fig. 7 is a side view of the razor bed-plate, the base of said plate being shown partly in section.

Figs. 8 and 9 are side views of a modified form of handle, together with a razor of the 45 well-known "Autostrop" type with which the handle is to be used.

Fig. 10 is a view of another modified form of handle similar to Fig. 9, but adapted for use with the "Gillette" type of razor.

50 In the use of former types of safety razors, great difficulty was experienced in holding the blade at the proper diagonal angle to the line of the shaving stroke, and the correct shaving stroke could be acquired only after 55 a considerable period of use.

By means of the present invention the

above and other disadvantages have been avoided. This has been accomplished by providing a safety razor with a flat handle set at such an angle to the blade that when 60 the handle is drawn across the face in a straight line, the blade will automatically assume the correct diagonal position with respect to the line of stroke.

Referring now to the drawings in which 65 like reference numerals denote corresponding parts throughout the several views, the numeral 10 indicates a bed-plate comprising a base formed in the shape of an oblique parallelogram and having its opposite sides 70 and ends parallel. The bed-plate 10 is crescent shape in transverse section and is provided with a pair of upstanding studs 11 and 12 near its ends, and an elongated cylindrical central post 13 having its upper portion 75 13^a threaded.

In order to prevent the razor blade from cutting the face of the user, a guard plate 14 is provided, said guard plate also being preferably arc-shaped in transverse section and 80 having its exterior face adapted to fit the interior face of the bed plate 10. The guard plate 14 is provided on its opposite sides with rows of teeth 15 and 16 respectively, 85 said teeth preferably lying parallel to the ends of the guard plate 14, as clearly shown in Figs. 2 and 5. The guard plate 14, is provided with a pair of apertures 17 adapted to fit over the studs 11 and 12, and also has a depressed annular recess 18 encircling an 90 aperture 19 within which the post 13 of the bed plate 10 is adapted to fit.

In order to clamp the guard plate 14 firmly upon the bed-plate 10 to secure a razor blade 20 therebetween, a cylindrical locking 95 tube 21 is provided, as clearly shown in Fig. 4. The locking tube 21 is preferably knurled on its lower exterior 22, and is provided with an upper reduced section 23. The inside bore of the locking tube is preferably 100 smooth and of uniform diameter throughout its length except for a short threaded top section 24, as shown in Fig. 4.

In order to manipulate the safety razor, a handle 25 is provided which as clearly 105 shown in Fig. 3 consists of a thin flat finger engaging portion 26 of a generally rectangular shape, having convex corners and concave side edges. The finger-engaging section of the handle 25 is preferably knurled 110 on its opposite faces. The handle 25 is provided at its lower section with a hollow

socket 27, tapped on its interior to engage the threads of the top 13^a of the post 13.

In Fig. 8, a modified form of handle is shown, said handle being adapted to be 5 screwed into a razor body of the "Autostrop" type shown in Fig. 9. This form of handle is preferably constructed by stamping and bending from a single strip of metal and comprises a thin flat upper section 28 and 10 a thin flat lower section 29, said sections 28 and 29 being at right angles to each other. The bottom of the lower section 29 has a rod 30 integrally secured thereto, said rod being threaded on its exterior to screw into a socket 15 31 of a razor body 32. By means of the safety razor shown in Figs. 8 and 9, when it is desired to shave the left side of the face, the upper section 28 of the handle will be grasped by the hand of the user. When, 20 however, the right side of the face is to be shaved, the lower section 29 of the handle will be employed.

In the operation of both forms of razor, the handle will be drawn along the face in 25 a straight line parallel to the line of stroke. This will cause the edge of the razor blade to be drawn along obliquely to the line of stroke. The handles of the razors are preferably adjusted so that the blade will make 30 an angle of approximately seventy-five degrees to the line of stroke, this angle having been found in practice to be the most efficient.

One advantage of the present invention 35 is that the improved safety razor herein disclosed may be used with equal success by unskilled as well as skilled persons. A further advantage is that a person shaving with the razor for the first time can obtain 40 the correct diagonal stroke which formerly required a long period of practicing to acquire.

While there have been disclosed in this 45 specification two forms in which the invention may be embodied, it is to be understood that these forms are shown for the purpose of illustration only, and that the invention is not to be limited to the specific disclosures but may be modified and embodied in various other forms without departing from its 50 spirit. In short, the invention includes all the modifications and embodiments coming within the scope of the following claims.

Having thus fully described the invention, 55 what is claimed as new, and for which it is desired to secure Letters Patent, is:

1. In a safety razor, a blade formed in the shape of an oblique parallelogram, a bed-plate to support said blade, a guard adapted 60 to be clamped upon said bed-plate, said bed-plate having a threaded post extending up-

wardly through said blade and guard, and a locking tube threaded on the end of said post for pressing said guard and bed-plate together to lock said blade therebetween. 65

2. In a safety razor, a blade formed in the shape of an oblique parallelogram, a bed-plate to support said blade, a guard adapted to be clamped upon said bed-plate, said bed plate having a threaded post extending up- 70 wardly through said blade and said guard, said post being threaded on its upper extremity, a threaded tube screwed on said post for clamping said blade between said bed-plate and guard, and a handle threaded on the top of said post for manipulating said razor. 75

3. In a safety razor, a blade formed in the shape of an oblique parallelogram, a bed-plate to support said blade, a guard adapted 80 to be clamped upon said bed-plate, said bed-plate having a threaded post adapted to extend upwardly through said blade and said guard, a locking tube threaded on said post for holding said blade clamped between said 85 guard and said bed-plate, and a handle threaded on the top of said post for manipulating said razor, said handle having a thin flat finger engaging section parallel 90 to the ends of said blade, and disposed at the correct shaving angle relative to the line of the shaving stroke. 95

4. In a safety razor, a blade formed in the shape of an oblique parallelogram, a holder 100 for said blade, a guard to protect the face of the user, said holder having a post projecting through said blade and said guard, a hollow tube threaded on said post, and adapted to engage said guard to clamp said blade between said guard and said holder, and a handle screwed on the top of said post 105 for manipulating said razor. 110

5. In a safety razor, a blade, a holder for said blade, a guard for said blade, a handle composed of two thin flat sections disposed 115 at right angles to each other and arranged obliquely to the edge of said blade whereby one handle section may be used when shaving the left side of the face, and the other handle section when shaving the right side of the face. 120

6. In a safety razor, a blade, a guard for said blade, a holder for said blade and said guard, and a handle connected to said holder, said holder having a pair of sections disposed at an angle to each other, one of said sections being adapted to be used when shaving one side of the face, and the other section when shaving the other side of the face. 125

In testimony whereof, I have affixed my signature to this specification.

FRED SEXAUER.
